TAG FASTENING DEVICE

Donald M. Swett, Chicago, and Sidney E. Van Tuyl, Riverside, Ill., assignors to American Tag Company, Chicago, Ill., a corporation of Illinois

Application January 30, 1942, Serial No. 428,826

13 Claims. (Cl. 93—88)

This invention relates to tag fastening devices and more particularly to devices for fastening tags or labels to merchandise by means of wire staples supplied separately from the tags.

One of the objects of the invention is to provide a tag fastening device in which tags in strip form are fed, cut from the strip, and stapled to the merchandise.

Another object of the invention is to provide a tag fastening device in which a strip of tags is fed in one direction and a series of staples to fasten the tags is fed in a direction at right angles thereto. Preferably, the staples are fed along one of the members forming an operating part of the device, and the tags are fed in from the side, so that the supply is always visible and does not interfere with use of the machine.

Another object of the invention is to provide a tag fastening device of the type referred to in which the parts are temporarily held in intermediate position and further tag feeding is prevented after completion of a fastening operation to permit easy removal of merchandise to which a tag has been fastened.

Still another object of the invention is to provide a tag fastening device for separately feeding tags and fastening staples, which is small and compact, so as to be readily portable for use in any location or position. According to one feature of the invention, the device is made in the form of a manually operable hand tool.

Other objects and advantages of the invention, including desirable operating features and structural arrangements, will be apparent from the following description when read in connection with the accompanying drawings, in which:

Figure 1 is a top view of a tag fastening device embodying the invention;

Figure 2 is a side elevation looking from the bottom of Figure 1;

Figure 3 is a perspective view showing the manner of feeding the tags and staples;

Figure 4 is a perspective of one of the lever elements;

Figure 5 is a view similar to Figure 2, showing the parts in another position;

Figure 6 is a view similar to Figure 2, with parts omitted;

Figure 7 is a view similar to Figure 6, in another position;

Figure 8 is a section on the line 8—8 of Figure 6;

Figure 9 is a perspective view of the tag holding and cutting plate;

Figure 10 is a section on the line 10—10 of Figure 2;

Figure 11 is a view similar to Figure 10 with the parts in the position of Figure 5;

Figure 12 is a section on the line 12—12 of Figure 2;

Figure 13 is a view similar to Figure 12 with the parts in the position of Figures 5 and 11;

Figure 14 is a partial section of the tag feeding means on the line 14—14 of Figure 1;

Figure 15 is a partial section on the line 15—15 of Figure 1; and

Figure 16 is a view similar to Figure 15 with the parts in another position.

15 The illustrated machine comprises three levers 17, 18 and 19, pivotally connected together at one end on parallel pivots 21. As shown, the lever 18 lies between the levers 17 and 19, and the three levers lie substantially in a common plane. A spring 22 urges the upper lever 17 and the intermediate lever 18 apart, and the two outer levers 17 and 19 are adapted to be drawn together by an operating handle 23, pivoted at 24 to the lever 19, with its end connected to the lever 17 by a link 25.

The intermediate lever 18, as best seen in Figures 10 to 13, is of inverted channel shape and carries a guide block 26 spaced from its sides to form a supporting and guiding channel for a series of pre-formed wire staples 27. The staples, as shown, are of substantially U-shaped form, and are connected together side-by-side by lacquer or other suitable adhesive, in the form commonly known as "frozen" staples. Adjacent its outer end, the intermediate lever 18 is formed with a feed slot or opening through which the end staple may pass, and the ends of the staple are adapted to be bent or crimped over by means of an anvil 28, carried by the free end of the lever 19. As shown in Figures 10 and 11, the end staple is adapted to be forced through the slot against the anvil by means of a blade 29 carried by the upper lever 17 in a position to press against the top edge of the end staple and force it through the slot and against the anvil when the levers are drawn together. The staples may be fed forwardly through the intermediate lever 18 by means of a spring, indicated at 31, held in place by a locking member 32 which may easily be removed for replenishing the staple supply when necessary.

Tags are adapted to be supplied to the device in strip form, as shown at 33 in Figure 3. As illustrated in this figure, a series of pre-formed tags may be connected in a strip, and each of

the tags may be formed with a central feed opening 34 and with a partially slotted edge 35. Tags of this character are more particularly described and claimed in the co-pending application of Sidney E. Van Tuyl, Serial No. 408,771, filed August 29, 1941, although it will be understood that tags of a different type could be used in the machine if desired.

The tags are supported on a guide plate 36 which is carried by a fourth lever 37 pivoted at 38 to the intermediate lever 18. An elongated slot 39 adjacent the free end of the lever 37 is adapted to fit over a screw 41 carried by the intermediate lever 18 to limit relative movement between the levers 18 and 37. The tags are held in place on the guide plate 36 by means of a plate 42 pivotally mounted on ears 43 formed adjacent the end of the guide plate to hold the tags thereon.

In order to feed the tags along the guide plate, a feeding carriage 44 is slidably connected thereto by means of pins passing through an elongated slot 45 in one side of the guide plate. The carriage is normally urged toward the lever 37 by means of a coil spring 46 connected at its opposite ends to the lever and the carriage. A flexible feed finger 47 is carried by the carriage 44 and has a turned-down tip 48 thereon, as shown in Figures 10 and 11, which is adapted to enter the openings 34 in the tags to feed them along the guide plate. The cover plate 42 is formed with a slot through which the finger 47 projects to engage the tags. Rearward movement of the tags during retraction of the feed carriage and feed finger is prevented by a flexible spring finger 49 having a turned-down end projecting through the slot in the cover plate 42 to engage the openings 34 in the tags.

The carriage is adapted to be moved to its feeding position against the tension of the spring 46 by means of a cam mechanism including a cam plate 51 connected to the upper lever 17 by means of an arm 52 secured to the cam plate. As shown, the arm 52 is formed with a transverse slot 53 at its upper end, slidably fitting over a pin 54 on the upper lever 17 and with an elongated slot 55 slidably fitting over a screw 56 on the lever 37. In this way, the arm 52 is guided and will be moved relative to the lever 37 upon relative movement between this lever and the upper lever 17. One edge of the cam plate 51 is cut at an angle, as shown in Figures 12 and 13, to engage a pin 57 carried by a lever 58 pivoted at its lower end on a flange 59 on the guide plate 36. As the cam plate moves down relative to the flange 59, the edge thereof will engage the pin 57 and rock the lever 58 clockwise, as seen in Figures 12 and 13. At its upper end the lever carries a pin 61 fitting in a vertical slot in the adjacent side of the feed carriage 44, so that as the lever is rocked, the carriage will be moved along the guide plate. The carriage 44 is adapted to be locked in its retracted position to prevent feeding of the tags except when desired by means of a latch 62 (Figure 15) pivoted on the flange 59 and having an end portion 63 adapted to project through an opening in the guide plate 36 to engage a corresponding latching opening 64 in the carriage 44. The latch is normally rocked to its latching position by a coil spring 65 and is adapted to be released by a pin 66 carried by cam plate 51 and operating in a vertical slot 67 in the flange 59. The pin 66, when in the position shown in Figure 15, engages the end

of the latch and rocks it clockwise to withdraw the ends 63 from the opening 64 to release the carriage.

The parts are adapted to be held in an intermediate position after completion of a fastening operation to permit ready withdrawal of material to which a tag has been stapled. For this purpose, the cam plate 51 is formed in one side with a cam groove 68, generally heart-shaped. A pin 69 carried by the end of a lever 71 pivoted to the flange 59, co-axial with the lever 58, is adapted to ride in this cam groove and to hold the parts in intermediate position, as will be explained hereinafter. As shown in Figure 14, the lever 71 is connected to the flange 59 by means of a pin carrying a cup spring 72 to hold the lever 71 frictionally in any position to which it has been moved. As the tags are fed across the guide plate 36, the end tag on the strip is moved into register with the free end of the intermediate lever 18 which is provided with a holding and cutting plate 73, as shown in detail in Figure 9. The plate 73 is formed with a slot 74 through which the staples are adapted to pass and has on its lower side turned-in flanges 75 to receive and hold the tags. As the tags are fed across the guide plate, they will slide in between the flanges 75 and will be yieldingly held thereby. In addition, the edge of the plate 73 adjacent the guide plate 36 serves as a cutting edge to sever the end tag on the strip. Cooperating with this edge of the plate, the guide plate 36 carries a blade 76, which is adapted to be moved across the edge of the plate 73 to cut the tag.

In order to move the lever 37 and the parts associated therewith during the cutting operation, a lug or finger 77 is carried by the guide plate and projects into the path of movement of the lower lever 19. As this lever is moved upwardly toward the upper lever 17, it engages and raises the lever 37 and the guide plate so that the end tag will be severed from the strip between the blades 76 and the edge of the plate 73.

In order to prevent relative movement between the upper lever 17 and the intermediate lever 18 during the severing operation, a latch mechanism, as shown in detail in Figures 6, 7 and 8, is provided. As shown in these figures, the pivotal connection between the handle 23 and the link 25 is formed by a pin having an enlarged head 78 lying on the inside of the link. With the levers in their open position, as shown in Figure 6, the enlarged head 78 overlies and rests on a cam block 79 secured to the side of the intermediate lever 18. Thus, any movement of the lever 18 toward the lever 17 will be prevented with the parts in this position. As the handle is moved to move the levers 17 and 19 together, the head 78 will move off of the block 79, thereby releasing the lever 18 for movement toward the lever 17. The cutting operation, however, is performed during such time as the head 78 is resting on the block 79, so that the lever 18 is rigidly held and cannot move toward the lever 17.

In operation, a strip of tags is placed on the guide plate 36 beneath the plate 42, as shown in Figure 1, and the intermediate lever 18 is loaded with a series of staples. A sheet of merchandise to be tagged may then be placed over the anvil 28 and the operator may squeeze the handle 23 toward the upper lever 17. During the initial part of this movement, the lever 19 will engage the finger 77 to move the lever 37 and the guide plate upwardly, thereby severing the end tag from the strip. At this time, the severed tag will

be held between the flanges 15 and further squeezing of the handle will raise the sheet of material on the anvil into engagement with the lower surface of the tag and will continue to elevate the guide plate 36 with respect to the intermediate lever 18. After the head 78 of the pivot pin has passed off of the cam block 79, the intermediate lever 18 may also be moved upwardly toward the upper lever 17 by engagement of the anvil and the material carried thereby with its lower surface. During this operation, the blade 29 will press the end staple through the opening in the intermediate lever and through the slot 74 in the plate 73, through the tag and material, and against the anvil 28, to be crimped over, as shown in Figure 11. This completes the first operation of fastening a tag to the sheet.

During this operation, the pin 69 on the lever 71 will travel in a general clockwise direction around the cam slot 68, and at completion of the fastening operation will lie in the upper part of the left lobe of this slot, as seen in Figures 12 and 13. When the handle 23 is released, the lower lever 19 will tend to drop away from the other parts and the pin 69 will fall into the intermediate part of the cam slot, as shown in Figure 13. This locks the parts against further separation, holding them in an intermediate position so that the material may be removed from the device. At this time, the feed carriage 44 has been moved to its outermost position and is held therein by the latch 62 with the parts in the position shown in Figure 16. Thus, no additional tags will be fed while the material is still in the device and during the time that it is being removed.

After the material has been removed, the handle 23 may again be squeezed to bring the ends of the levers together, the pin 69 travelling at this time to the upper part of the right lobe of the cam slot 68, as seen in Figures 12 and 13. Upon again releasing the handle, the pin 69 will travel down the right side of the cam slot into the lower part thereof, permitting the levers to separate to their maximum extent, as shown in Figure 2. When this occurs, the cam plate 51 moves up relative to the flange 59 causing the pin 66 to rise in the slot 67 to engage the end of the latch 62, releasing the feed carriage 44 so that it may move toward the levers under the influence of spring 46. During this movement, the feed finger 47, which has engaged the feed opening 34 of the second tag from the end of the strip, will move the strip of tags in a feeding direction to cause the end one thereof to register with the holding and cutting plate 73. At this time the parts are in condition for a succeeding fastening operation, and the operations may be repeated as described above to secure any desired number of tags to merchandise.

While one embodiment of the invention has been shown and described in detail, it will be understood that this is illustrative only, and is not to be taken as a definition of the scope of the invention, reference being had for this purpose to the appended claims.

What is claimed is:

1. A tag fastening device comprising a plurality of elongated members pivotally connected together, means for feeding a series of preformed staples lengthwise in one of the members, means carried by another of the members to feed a strip of tags in a direction transverse to the length thereof, means on said one of the members to receive and hold the end tag on the strip below the end one of the series of staples, cooperating means on said two members to sever the end tag

from the strip, and means on a third of the members to force the end staple through the severed tag and into a body of material underlying it.

2. A tag fastening device comprising a plurality of elongated members pivotally interconnected adjacent one end with their free ends movable relatively toward and away from each other, means carried by an intermediate one of the members for feeding a series of preformed staples lengthwise of the member toward the free end thereof, means carried by a second one of the members for feeding a strip of tags transversely of its length across the free end of said one member, cooperating means carried by the free ends of the first and second members to sever the end tag from the strip, means carried by a third of the members to force the end one of the series of staples through the severed tag and into a body of material underlying it when the third member is moved relatively toward the first member, and means to prevent movement of the third member toward the first member until after the end tag has been severed.

3. A tag fastening device comprising a plurality of elongated members pivotally interconnected adjacent one end with their free ends movable relatively toward and away from each other, means carried by an intermediate one of the members for feeding a series of preformed staples lengthwise of the member toward the free end thereof, means carried by a second one of the members for feeding a strip of tags transversely of its length across the free end of said one member, cooperating means carried by the free ends of the first and second members to sever the end tag from the strip, means carried by a third of the members to force the end one of the series of staples through the severed tag and into a body of material underlying it when the third member is moved relatively toward the first member, means to move the second and third members relatively together, and means to prevent movement of the first member toward the third member during initial operation of the last named means whereby the first and second members will be moved relative to each other to sever the end tag from the strip.

4. A tag fastening device comprising a plurality of elongated members pivotally interconnected adjacent one end with their free ends movable relatively toward and away from each other, means carried by an intermediate one of the members for feeding a series of preformed staples lengthwise of the member toward the free end thereof, means carried by a second one of the members for feeding a strip of tags transversely of its length across the free end of said one member, cooperating means carried by the free ends of the first and second members to sever the end tag from the strip, means carried by a third of the members to force the end one of the series of staples through the severed tag and into a body of material underlying it, when the third member is moved relatively toward the first member, an anvil carried by the free end of a fourth of the members to crimp over the ends of the staple, operating means connecting the third and fourth members to move them relatively together, the fourth member engaging the second and first members successively to move them toward the third member.

5. A tag fastening device comprising a plurality of elongated members pivotally interconnected adjacent one end with their free ends

movable relatively toward and away from each other, means carried by an intermediate one of the members for feeding a series of preformed staples lengthwise of the member toward the free end thereof, means carried by a second one of the members for feeding a strip of tags transversely of its length across the free end of said one member, cooperating means carried by the free ends of the first and second members to sever the end tag from the strip, means carried by a third of the members to force the end one of the series of staples through the severed tag and into a body of material underlying it when the third member is moved relatively toward the first member, an anvil carried by the free end of a fourth of the members to crimp over the ends of the staple, operating means connecting the third and fourth members to move them relatively together, the fourth member engaging the second member to move it relatively toward the first member to cut the end tag from the strip, and means to prevent movement of the first member toward the third member during the cutting operation.

6. A tag fastening device comprising three elongated levers pivotally connected together adjacent one end, means carried by the intermediate lever to feed a series of preformed staples toward the free end thereof, operating means to move the two outer levers together with the intermediate lever between them, means carried by one of the outer levers to force the end one of the series of staples from the intermediate lever, an anvil carried by the other outer lever to bend over the ends of the staple, a fourth lever pivoted to one of the first named levers, means carried by the fourth lever to feed a strip of tags successively across the end of the intermediate lever, means on the intermediate and fourth levers operable upon relative movement thereof to sever the end tag from the strip, and interengaging means on one of the end levers and the fourth lever to move the fourth lever relative to the intermediate lever during initial actuation of the operating means.

7. A tag fastening device comprising three elongated levers pivotally connected together adjacent one end, means carried by the intermediate lever to feed a series of preformed staples toward the free end thereof, operating means to move the two outer levers together with the intermediate lever between them, means carried by one of the outer levers to force the end one of the series of staples from the intermediate lever, an anvil carried by the other outer lever to bend over the ends of the staple, a fourth lever pivoted to one of the first named levers, means carried by the fourth lever to feed a strip of tags successively across the end of the intermediate lever, means on the intermediate and fourth levers operable upon relative movement thereof to sever the end tag from the strip, interengaging means on one of the end levers and the fourth lever to move the fourth lever relative to the intermediate lever during initial actuation of the operating means, and interengaging means on the intermediate lever and the other end lever to prevent relative movement thereof during initial actuation of the operating means.

8. A tag fastening device comprising three elongated levers pivotally connected together adjacent one end, means carried by the intermediate lever to feed a series of preformed staples toward the free end thereof, operating means to move

the two outer levers together with the intermediate lever between them, means carried by one of the outer levers to force the end one of the series of staples from the intermediate lever, an anvil carried by the other outer lever to bend over the ends of the staple, a fourth lever pivoted to one of the first named levers, means carried by the fourth lever to feed a strip of tags successively across the end of the intermediate lever, means on the intermediate and fourth levers operable upon relative movement thereof to sever the end tag from the strip, a lug carried by the fourth lever and projecting into the path of movement of said other of the outer levers to move the fourth lever relative to the intermediate lever, and interengaging means on the intermediate lever and said one of the outer levers to prevent relative movement therebetween during initial movement of the outer levers together.

9. A tag fastening machine comprising a plurality of elongated levers pivotally connected together adjacent one end, means carried by an intermediate lever to feed a series of preformed staples toward the free end thereof, means to support a strip of tags adjacent the free end of said lever, means to cut the end tag of the strip therefrom, means carried by a second lever to force the end staple of the series through the tag and into a body of material underlying it, an anvil on a third lever to crimp over the ends of the staple when the free ends of the lever are moved together, feeding means for the strip of tags urged in a feeding direction by a spring, cam means operated by a relative pivotal movement of the levers to move the feeding means in the other direction, a latch to hold the feeding means in its extreme position in said other direction, and means operable upon movement of the levers to their maximum separated position to release the latch.

10. A tag fastening machine comprising a plurality of elongated levers pivotally connected together adjacent one end, means carried by an intermediate lever to feed a series of preformed staples toward the free end thereof, means to support a strip of tags adjacent the free end of said lever, means to cut the end tag of the strip therefrom, means carried by a second lever to force the end staple of the series through the tag and into material underlying it, an anvil on a third lever to crimp over the ends of the staple when the free ends of the levers are moved together, feeding means for the strip of tags urged in a feeding direction by a spring, cam means operated by relative pivotal movement of the levers to move the feeding means in the other direction, a latch to hold the feeding means in its extreme position in said other direction, means operable upon movement of the levers to their maximum separated position to release the latch, and a second latch means engaged by movement of the levers together to hold the levers in a partially opened position and released by again moving the levers together.

11. A tag fastening device in the form of a portable hand tool comprising three levers pivotally connected together adjacent one end, an operating handle pivoted to one of the outer levers and linked to the other to move them together, means on the intermediate lever to feed a series of preformed staples longitudinally thereof, means on the outer levers to force a staple from the feeding means and to bend over the ends thereof when the levers are moved together, a fourth lever pivotally connected to the first named

levers, means on the fourth lever to feed a strip of tags transversely thereof successively into register with the intermediate lever, and cooperating means on the intermediate and fourth levers to cut the end tag from the strip when said levers are moved relative to each other.

12. A tag fastening device in the form of a portable hand tool comprising three levers pivotally connected together adjacent one end, an operating handle pivoted to one of the outer levers and linked to the other to move them together, means on the intermediate lever to feed a series of preformed staples longitudinally thereof, means on the outer levers to force a staple from the feeding means and to bend over the ends thereof when the levers are moved together, a fourth lever pivotally connected to the first named levers, means on the fourth lever to feed a strip of tags transversely thereof successively into register with the intermediate lever, cooperating means on the intermediate and fourth levers to cut the end tag from the strip when said levers are moved relative to each other, the fourth lever having a part engageable with one of the end levers to

move the fourth lever when the handle is operated.

13. A tag fastening device in the form of a portable hand tool comprising three levers pivotally connected together adjacent one end, an operating handle pivoted to one of the outer levers and linked to the other to move them together, means on the intermediate lever to feed a series of preformed staples longitudinally thereof, means on the outer levers to force a staple from the feeding means and to bend over the ends thereof when the levers are moved together, a fourth lever pivotally connected to the first named levers, means on the fourth lever to feed a strip of tags transversely thereof successively into register with the intermediate lever, cooperating means on the intermediate and fourth levers to cut the end tag from the strip when said levers are moved relative to each other, and means effective during initial movement of the handle to prevent movement of the intermediate lever toward the other end lever.

DONALD M. SWETT.
